DESIGN FOR A PERFUME CONTAINER OR THE LIKE

Bertha H. Ogden, New York, N. Y., assignor to
Babs Creations, Inc., New York, N. Y., a corporation of New York

Application February 14, 1940, Serial No. 90,246

Term of patent 3½ years

To all whom it may concern:

Be it known that I, Bertha H. Ogden, a citizen of the United States and a resident of the city of New York (Borough of Manhattan) county and State of New York, have invented a new, original, and ornamental Design for a Perfume Container or the like, of which the following is a specification, reference being had to the accompanying drawing, forming part thereof, in which—

The dominant feature of my design resides in the provision of a substantially heart-shaped bottle supported by a pair of upwardly extending hands arranged substantially in the manner shown.

I claim:

The ornamental design for a perfume container or the like, substantially as shown and described.

BERTHA H. OGDEN.
